UNITED STATES PATENT OFFICE.

WALTER F. HAMMEL, OF CHICAGO, ILLINOIS, ASSIGNOR, BY MESNE ASSIGNMENTS, TO
NEOSTYLE ENVELOPE COMPANY, OF CHICAGO, ILLINOIS, A CORPORATION OF
ILLINOIS.

ENVELOP.

1,230,154.

Specification of Letters Patent. Patented June 19, 1917.

Application filed December 13, 1913. Serial No. 806,435.

To all whom it may concern:

Be it known that I, WALTER F. HAMMEL, a citizen of the United States, and a resident of Chicago, in the State of Illinois, 5 have invented certain new and useful Improvements in Envelops, of which the following is a specification.

My present invention relates in general to envelopes, and more particularly to envelopes 10 of the type known as "penny-savers" wherein there is a portion which may be opened by the postal authorities for the inspection of the contents thereof or for the removal of such contents for such inspection, and has special reference to improvements 15 in envelopes of the character referred to in which the so-called loose portion or flap is normally engaged and held from opening out by another portion of the structure or by the relative disposition of the parts.

The principal objects of my present invention are the provision in an envelop of the type referred to of improved means 20 whereby the loose flap is normally retained in predetermined closed position by means of the back of the envelop; the provision of a coöperative hook and slot on said flap and back in aid of such purpose; the provision of an envelop of the class referred 25 to characterized by the availability of the entire back of the structure for engagement by the sealing flap folded rearwardly from the front portion thereof, whereby the finished structure is greatly strengthened, and 30 this without danger of accidental engagement of the loose flap by such sealing flap, together with such other objects as may be hereinafter disclosed.

40 In gaining the foregoing objects and certain additional benefits and advantages, which will herein below appear, I have provided a structure, one embodiment of which is illustrated in the accompanying drawing, 45 wherein—

Figure 1 is a diagrammatic view of blank from which is made an envelop embodying a preferred form of my present invention, the dotted lines representing the creases 50 formed in folding the blank in the course of the manufacture of the article;

Figs. 2, 3 and 4 are similar views showing the consecutive steps of folding in such manufacture; and

Figs. 5 and 6 are respectively a back view 55 of the completed article, and a sectional view thereof with an inclosure therein.

Referring first to Fig. 1 of the drawing, it will be noted that the envelop herein illustrated is distinctly of the "high-back" type, 60 and comprises the customary portions, viz.: a front, A, a back, B, side or end flaps, C—D, and a top or sealing flap, E.

In carrying out my invention I have provided on the back, B, a supplemental portion, F, which I will term the "back-fold," and where desirable I employ in connection therewith one or more elongated slotted apertures G, G, adapted for the reception of upward projections H, H, preferably 70 hook shaped, formed on the flaps, C, D.

In the manufacture of the envelop, folds are consecutively made on the lines j, k and m in the customary manner, such steps being illustrated in Figs. 2 and 3 respectively, whereupon the projections H, H, 75 are introduced into the openings G, G (see Fig. 3), and the flap F folded over inwardly along the line p, thus producing the arrangement shown in Fig. 4.

On examination of Fig. 4 it will be apparent that the end flaps C, D, are substantially covered by the back B and embraced closely between it and the back fold F, which holds them securely in position. 85 As it is of importance that the flaps C and D be left unconnected, they are preferably of less total length than the length of the back B.

The sealing flap E is shown as provided 90 with the customary adhesive portion, which may be provided thereon throughout the usual full portion of its length as indicated by the stippling z and sealed down against the back B, without danger of unintentionally securing the end flaps C, D, against 95 opening, in view of the extreme width of the back B and the manner in which it covers the end flaps C, D.

Ordinarily, I prefer to omit the projection H on one of the flaps, such as the flap C, and likewise the corresponding aperture G, and in such cases preferably cause such flap to adhere to the back B by means of an adhesive applied to a portion of the flap, as 100 indicated by the stippling at x, such flap C then becoming a "closed flap" but the flap D remains an "open flap."

Those skilled in the art to which my invention pertains will appreciate that while the coöperating hooks and openings H—H, G—G, are highly advantageous, for 5 certain purposes one or both may be omitted, that the adhesive α may be applied indifferently to the flap C or to the flap D, or to an opposite portion of the back, and that aside from the "penny-saver" features 10 of my improved envelop which afford a maximum of strength, the most desirable appearance, and the minimum of difficulties in manufacture, articles may be inserted into such envelop with the greatest 15 of facility and despatch and with a minimum of loss of time either from accidental derangement of the folds or from catching or other interference by such folds or with such insertions or inclosures.

20 I am aware that it has heretofore been proposed to form an envelop having a front portion A provided with a flap E and a back portion B provided with a flap F and likewise overlapping flaps C and D, such latter 25 flaps, being caused to adhere together and the flap B being caused to adhere to both of said flaps C and D, and also that it has heretofore been proposed to form an interlocking engagement between the flap E and 30 a slot in one of the flaps C, D, and consequently the structures referred to are not intended to be included within the scope of my claims.

On viewing Fig. 4 of the drawing it will 35 be observed that the line of folding between the back portion B and the flap F renders such back portion of a height less than the height of the front portion A, which permits the projections HH to protrude 40 through the apertures GG without bending such projections, and is furthermore advantageous in this that it provides a lock adjacent each corner of the envelop between said back and end portions, when the envelop 45 is in its normal flat condition. This structure is not only advantageous in the points thus defined, but has this further advantage that on bending the envelop in the customary manner to facilitate the insertion of a finger to withdraw the flap C such bending causes the disengagement of the hook H with the aperture G and thus permits ready pulling out of the flap C without tearing or bending the projection or enlargement of the aperture G.

Having thus described my invention and illustrated its use, what I claim as new and desire to secure by Letters Patent is:

1. An envelop having front and back portions, and an end portion interposed between said front and back portions, the back portion being provided with a locking flap folded inwardly toward the front portion and against the back, whereby the end portion is embraced between said back and flap,

the locking flap and end portions being provided respectively with a coöperating aperture and projection whereby they may be brought into engagement.

2. An envelop having front and back portions and an end portion, the back portion being provided with a locking flap folded inwardly toward the front portion and against the back whereby the end portion is embraced between said back and flap, the locking flap and end portions having coöperating aperture and projection engagement, and the front being provided with a sealing flap having an adhesive for engaging the back of the envelop, and covering said aperture and projection engagement.

3. An envelop having front and back portions and an end portion, the back portions being provided with a locking flap folded inwardly toward the front portion and against the back whereby the end portion is embraced between said back and flap, the locking flap and end portions having coöperating aperture and projection engagement, and the front being provided with a sealing flap having an adhesive for engaging the back portion only, the end portion being left free from adhesive engagement with any part of the envelop, whereby it may readily be withdrawn.

4. An envelop having front and back portions and a pair of oppositely disposed end portions, the back being provided with a locking flap folded inwardly toward the front portion and against the back, whereby one of the end portions is embraced between said back and flap, said locking flap and one of said end portions having coöperating aperture and projection engagement, said back being also provided with an adhesive engagement with one of said end portions, the other end portion being left free to be pulled out.

5. An envelop having front and back portions and a pair of oppositely disposed end portions, the back being provided with a locking flap folded inwardly toward the front portion and against the back, whereby one of the end portions is embraced between said back and flap, said locking flap and one of said end portions having coöperating aperture and projection engagement, the front being provided with a sealing flap having an adhesive for engagement with said back portion only, one of the end portions being left free from adhesive engagement so that it may be pulled out.

6. An envelop having front and back portions, and an end portion having a marginal projection, the back portion being provided with a supplemental portion having a marginal aperture for engagement with said projection, and a retaining flap engageable with the back and disconnected from said end portion.

7. An envelop having front and back portions, and an end portion having a marginal projection, the back portion being provided with a supplemental portion having a marginal aperture for engagement with said projection, and the front being provided with a sealing flap having an adhesive for engaging the back of the envelop and covering said aperture and projection engagement and free from connection with said end portion.
8. An envelop having front and back portions, and an end portion having a projection, a locking flap provided with an aperture for engagement with said projection, and the front being provided with a sealing flap arranged at substantially a right angle to said end portion and having an adhesive for engaging the back portion only and covering said aperture and projection engagement, the end portion being left free from adhesive engagement so that it may be withdrawn.
9. An envelop having front and back portions, and a pair of oppositely disposed end portions one having a projection, the back being provided with a flap apertured adjacent its line of fold for engagement with said projection, and said back being provided with an adhesive for engagement with one of said end portions, the other end portion being left free and unconnected with the back whereby it may be freely withdrawn.
10. An envelop having front and back portions and an end portion having a marginal projection, the back portion being provided with a flap folded inwardly toward the front portion and folded against the back and apertured along the line of the last mentioned fold for engagement with said marginal projection of the end portion.
11. An envelop having front and back portions and an end portion provided with a marginal projection, the back portion being provided with a flap apertured for engagement with said projection, said flap being folded inwardly toward the front portion and against the back, and with an aperture for engaging said projection, whereby said back and end portions are locked together adjacent one of the edges of the envelop, and said front portion being provided with a flap engaging with said back portion only and covering the locking point between said back and end portions.
12. An envelop having front and back portions and a short end portion provided with a marginal projection the back portion being provided with a flap apertured for engagement with said projection, said flap being folded inwardly toward the front portion and folded against the back, and with an aperture disposed away from said first mentioned line of fold for engaging said
- projection, whereby said back and end portions are locked together adjacent one of the margins of the envelop.
13. An envelop having front and back portions and an end portion provided with a marginal projection, the back portion being provided with a flap apertured for engagement with said projection, said flap being folded inwardly toward the front portion and folded against the back and with an aperture disposed away from said first mentioned line of fold for engaging said projection, whereby said back and end portions are locked together adjacent one of the margins of the envelop, and said front portion being provided with a flap engaging with said back portion only and covering the locking point between said back and end portions.
14. An envelop having front and back portions and an end portion provided with a hook, the back portion being folded inwardly to present a surface of less height than the height of said front portion, said back portion being provided with a flap apertured along the line of fold and having an engagement with said back portion, whereby engagement between the hooked and apertured portions may be effected without bending the hook, and the point of engagement between the back and end portions is covered by a flap on the front portion, but said end portion may be withdrawn on bending the envelop.
15. An envelop having front and back portions and an end portion provided at its upper edge with a hook, the back portion being folded inwardly to embrace said end portion and to present a surface of less height than the height of said front portion, said back portion having an elongated aperture adjacent the line of fold of said back portion to receive said hook, whereby the structure is rendered expansible, and whereby said engagement between the back and end portion is covered, but said end portion is left free to be withdrawn.
16. An envelop having a front and a back, said back comprising two end flaps lying against the front, a bottom flap lying against the outer surfaces of the end flaps, and a top or sealing flap lying against the outer surfaces of all of the other flaps, one of the end flaps being permanently united to the bottom flap and the other of said end flaps being loose and provided on one of its edges with a tongue, and some part of the envelop being provided with an aperture located in position to receive said tongue and through which said tongue projects.
17. An envelop having a front and a back, said back comprising two end flaps lying against the front, a bottom flap lying against the outer faces of the end flaps and a top or sealing flap adapted to overlap and lie

against the outer surface of the bottom flap, that portion of the sealing flap which overlaps the bottom flap being provided with gum for securing it thereto when the envelope is closed and sealed, the bottom flap being permanently secured to one of the end flaps and the other end flap being left loose and free to be withdrawn from its closed position, the loose flap being provided at its top edge with a tongue or projection and

some part of the envelope being provided with an aperture located in position to receive said tongue or projection.

In testimony whereof I have hereunto signed my name in the presence of the two 15
subscribed witnesses.
